UNITED STATES PATENT OFFICE.

CARL W. WEISS, OF NEW YORK, N. Y.

EXPLOSIVE-ENGINE.

SPECIFICATION forming part of Letters Patent No. 704,995, dated July 15, 1902.

Application filed January 15, 1900. Serial No. 1,474. (No model)

To all whom it may concern:

Be it known that I, CARL W. WEISS, a citizen of the United States, residing in the borough of Manhattan, city of New York, State 5 of New York, have invented certain new and useful Improvements in Explosive-Engines, of which the following is a specification, reference being had to the accompanying drawings, forming a part hereof.

10 This invention relates to the general class of explosive-engines in which the explosive mixture is formed in the working cylinder or explosion-chamber, a liquid hydrocarbon or a previously-formed gas being introduced into 15 such cylinder or chamber and there mixed with air.

One object of the invention is to provide for a reduction of the temperature of the explosion-chamber, and consequently of the 20 fresh charge as it is introduced, so that a higher degree of compression can be reached without ignition and the efficiency of the engine increased.

A further object is to provide for a thorough clearing out of the dead gases from the 25 explosion-chamber after each explosion.

A further object, particularly applicable to engines of this class with which a previously-formed gas is made the basis of the explosive 30 mixture, is to guard against the retention of any explosive mixture in the ports or passages leading to the explosion-chamber, such retention of explosive mixture leading to secondary explosions, which, at least, impair the 35 efficiency of the engine; if they do not cause injury to its working parts.

To effect the cooling of the explosion-chamber and the clearing out of the dead gases, a small quantity of water is introduced into 40 the explosion-chamber in advance of the formation therein of the explosive mixture, the water so introduced being instantly vaporized, absorbing heat and driving out the dead gases which then remain in the chamber.

45 The relative time at which the water is introduced is of the essence of this part of the invention. It has been proposed heretofore to introduce a small quantity of water into the explosion-chambers of engines of this class 50 at or immediately after the instant of ignition, with the idea of utilizing the expansive force of the steam thus generated for power behind

the moving piston. Incidentally the vaporization of the water would reduce the temperature within the cylinder; but such reduction 55 would not be so related to the formation and subsequent compression of the explosive mixture as to have any material effect upon the extent to which the compression could be carried. Furthermore, in the present case the 60 vaporization of the water is not utilized for power and has no effect whatever upon the movement of the piston. The vapor is formed and practically leaves the explosion-chamber while the piston is at the forward end of its 65 stroke. Such vapor of water as remains in the cylinder during the compression-stroke of the piston is inconsiderable and has less effect in reducing the efficiency of the mixture than would the dead gases which have been 70 expelled by it. It will be evident that this part of the invention is not limited to any particular form of engine or of devices with which it is practiced; but in order that its nature may be clearly understood certain convenient 75 embodiments thereof are shown in the accompanying drawings and will be described hereinafter.

In the drawings, Figure 1 is a view, partly in elevation and partly in vertical central section, of so much of a liquid-hydrocarbon engine as is necessary to enable the application of the first part of the present invention to be understood. Fig. 2 is a similar view, on a somewhat larger scale, of a portion of a gas- 80 engine which embodies both parts of the invention. Fig. 3 is a section on the irregular plane indicated by the dotted line 3 3 of Fig. 2, and Fig. 4 is a section on the plane indicated by the line 4 4 of Fig. 2. 90

Referring first to the embodiment of the invention represented in Fig. 1, the engine being therein shown as a liquid-hydrocarbon engine, the cylinder A of the engine is shown as of ordinary construction and provided with 95 the usual water-jacket A', while the casing A² is extended forward to inclose the crank and to receive the bearings of the crank-shaft. The usual trunk-piston B is shown as connected by a pitman B' to a crank-pin B², carried by crank-arms or crank-disks, one of which is shown as secured directly to the corresponding part of the crank-shaft C. The chamber inclosed by the forward part of the

casing A² constitutes, as is well understood, a convenient air-compression chamber in which the air admitted through a suitable port which is covered by the piston in its forward movement, but opened as the piston reaches the limit of its rearward movement, is compressed at each forward movement of the piston. The chamber is connected with the working cylinder A or explosion-chamber through a port 5 a, which is closed by the piston except when the latter is at or near the limit of its forward movement. An exhaust-port a' is also arranged so as to be closed by the piston except when the same is at or near the limit of its 10 forward movement. The cylinder-head A³ is represented as provided with an extension A⁴ to inclose an igniter, which is not necessary to be shown or described herein. In this engine the oil which forms the basis of the explosive charge is delivered to the cylinder through a discharge-nozzle, (indicated at H,) the oil being immediately vaporized and mixed with the air which is delivered through the port a when the piston is in its extreme 15 forward position. The source of supply of the oil is not necessary to be shown and may be of any suitable character.

As stated hereinbefore, a small quantity of water is introduced into the cylinder or explosion-chamber just before the formation of the explosive mixture. It may therefore be introduced conveniently through the supply-port a and may be supplied from any convenient source. As shown in the drawings, 20 Fig. 1, it is supplied from the water-jacket A', to which connection is made through a suitable stop-valve a⁸, check-valve a⁴, regulating-valve a⁵, and sight-feed a⁶. The water thus supplied falls into the port a while the latter is closed by the piston and remains there, either in a liquid form or as steam, until the port is opened just as the piston approaches the forward limit of its stroke. Then the water is discharged into the cylinder in 25 spray in advance of the incoming air and necessarily before the formation of the explosive mixture. It is immediately vaporized, cooling the walls of the cylinder by the absorption of heat and by its expansion driving out through the exhaust-port a' the dead gases which remain within the cylinder or explosion-chamber. It will be understood that although the whole operation is almost instantaneous, nevertheless the introduction of the water in 30 order to carry out the invention and to secure the results desired must be and is in advance of the formation of the explosive mixture and that its introduction after the formation of the explosive mixture and after the closing 35 of the exhaust-port would defeat the object of the invention.

It will be evident not only that the practice of the invention is independent of the particular devices employed, but that the invention is applicable to gas-engines as well as to oil-engines, and in Fig. 2 is illustrated an application of the invention to a gas-engine

of a well-known type. For convenience the cylinder A, with its water-jacket A', compression-chamber A², connected with the cylinder, and piston B, are represented substantially as in Fig. 1. The gas, which in this case forms the basis of the explosive mixture, is delivered to the supply-port a from a pump D, which receives it through a supply-pipe d (see Fig. 3) and check-valve d', the pipe d² serving both as a supply-pipe and a discharge-pipe for the pump. The gas is delivered through a valve-chamber E, and the time of delivery is controlled by a valve F, which is represented as carried by a rod f and held to its seat by a spring f'. The rod f may be operated as fully described in Letters Patent of the United States, No. 592,033, dated October 19, 1897, having upon its end a tongue f², 80 adapted to be struck by the end of a rod c', which is reciprocated by suitable connections from the engine-shaft, the action being controlled by a governor, as described in said patent. A small cylinder E' is extended from the valve-chamber E in line with the rod f and is connected with the water-jacket A' through a check-valve a⁴. An extension f⁴ of the rod f, having a spring-seated valve f⁵, which opens inward, forms a pump-bucket, 85 the valve-chamber communicating through a passage f⁶ in the rod f with the valve-chamber E, which is above the supply-port a. It will be obvious that at each reciprocation of the rod f a small quantity of water will be 90 delivered into the supply-port a and that such water will be delivered into the explosion-chamber or cylinder, as described above with reference to Fig. 1, the instant that the port a is opened by the movement of the piston to 95 its forward position, and consequently in advance of the introduction of the gas and before the formation in the cylinder of the explosive mixture. In this arrangement, moreover, the injection of water is subject to the 100 control of the governor above referred to and is therefore timed and controlled by and with the feeding of the fuel. This is an advantage, since it assures a proper and practical proportion between the supply of water and the 105 supply of fuel, or, in other words, the amount of heat. A constant supply of water, particularly when the engine is running with a light load, would tend to reduce the temperature of the vaporizer or igniter too much, and 110 a constant supply with the engine running under varying loads is undesirable. The action of the water in this case will be the same as already described with reference to the engine shown in Fig. 1.

In a gas-engine, as hereinbefore pointed out, it is desirable to guard against the retention outside of the cylinder of any of the explosive mixture, which might cause a secondary explosion. This object is attained 115 by making the air-supply port or ports a⁷ independent of the gas-supply port a, the gas-supply port and the air-supply port or ports terminating independently at the inner face

of the cylinder-wall. As the gas-port is filled with gas alone until it is covered by the piston in its rearward movement, it is obviously impossible for any air to become mixed with the gas which remains in the port. Likewise, since the air-ports are also cut off by the piston it is impossible for any gas to be mixed with the air therein. Consequently there can be formed in the supply-ports no explosive mixture which is liable to cause a secondary explosion. Neither is there any waste of gas, since the gas which remains in the gas-supply port cannot burn, as there is present no supporter of combustion.

15 The mode of operation of the several features of construction shown and described herein has been set forth already and will require no further explanation. It will also be evident that the invention is not restricted to the details of construction and arrangement shown and described herein, but may be embodied in many different forms.

I claim as my invention—

1. In an explosive-engine, the combination with an explosion chamber or cylinder having a supply-port and an exhaust-port opened

as the piston approaches the limit of its forward stroke, of means to introduce water into the chamber or cylinder as said ports open, whereby the water precedes the explosive 30 charge.

2. In an explosive-engine, the combination with a cylinder having supply and exhaust ports opened by the piston as it approaches the forward limit of its stroke, and means to 35 discharge water through said supply-port as it opens.

3. An explosion-engine having independent air and gas supply ports terminating in the inner surface of the cylinder-wall and means 40 to close said ports at their extremities.

4. An explosive-engine having independent air and gas supply ports terminating separately in the inner surface of the cylinder-wall and uncovered by the piston in its forward 45 movement.

This specification signed and witnessed this 12th day of January, A. D. 1900.

CARL W. WEISS.
